CASING ELEVATOR CONSTRUCTION

Chester A. Lundeen, Los Angeles, Calif., assignor
to Byron Jackson Co., Los Angeles, Calif., a cor-
poration of Delaware

Application January 23, 1933, Serial No. 653,074

5 Claims. (Cl. 294—90)

This invention relates to the construction of elevators such as used in handling casings at oil well derricks or the like. This improvement relates particularly to a type of elevator formed of two sections which are hinged together, so that they can be unlatched and swung outwardly to an open position. Each section of the elevator is provided with a lug or ear for engaging an elevator link corresponding to it, and these two 10 links are supported on a hoisting hook. In the use of the elevator it is necessary that the elevator should open freely to permit the hinged sections to be clasped around the well casing. It is also necessary that the elevator shall remain 15 open while being raised to the top of the oil derrick. When used with elevators having the usual lugs or ears which are radial to the axis of the elevator, the elevator is difficult to open and sometimes even impossible to open without lowering the hook or disengaging the bails from the lugs. Also the links tend to close the elevator 20 sections when they are left open.

An elevator has come into use that overcomes this difficulty, in which the lugs or ears are 25 curved, and this has occasioned the general discarding of elevators with radial lugs, and with a consequent considerable economic loss.

The general object of this invention is to provide in an elevator construction a link, which 30 will enable the elevator to be readily opened, and which will overcome the tendency of the elevator to close when in its open position, and at the same time, employing radial supporting ears or lugs on the elevator, thereby enabling the discarded elevators of this type to be put into use 35 again.

Further objects of the invention will appear hereinafter.

The invention consists of the novel parts and 40 combination of parts to be described hereinafter, all of which contribute to produce an efficient casing elevator construction.

A preferred embodiment of the invention is described in the following specification, while the 45 broad scope of the invention is pointed out in the appended claims.

In the drawings:

Figure 1 is a perspective illustrating an elevator construction, representing the elevator in an 50 open position and with the elevator links supported on an elevator hook, the upper portion of which is broken away.

Figure 2 is a horizontal section taken through the elevator links just above the elevator, and 55 illustrating the elevator in its closed position.

This view is of a diagrammatic nature, and omits the latch illustrated in Figure 1, for holding sections of the elevator in their closed position.

Figure 3 is a view similar to Figure 2, but illustrating the elevator in its open position.

Figure 4 is a side elevation of an elevator link embodying my invention.

Figure 5 is an edge elevation of the link illustrated in Figure 4, and further illustrating the distinctive features of this link.

Figure 6 is a view similar to Figure 5, but illustrating a slight modification in the form of the lower end of the link.

Figure 7 is a side elevation of a link of a different type, which is adapted to be formed as a weldless link, and this view illustrates an embodiment of my invention as applied to this type of link.

Referring more particularly to the parts, and especially to Figure 1, 1 and 2 indicate the two sections of the elevator 3, which are connected 75 together by a hinged connection 4. This view shows the elevator in its open position. The elevator can be opened in this way after releasing the latch 5. Each of the sections 1 and 2 is provided with radially projecting means such as an ear 6, which, if desired, may be formed on its under side with a recess 7 forming a rudimentary socket to engage the lower end of its corresponding link. In this view, 8 represents the left-hand link, and 9 the right-hand link.

These links are formed alike, except that one is a right-hand and the other a left-hand link. The link 8 is illustrated more in detail in Figures 4 and 5. This link is of the open or "hairpin" type, that is to say, it comprises a pair of oppositely disposed reins 10 which are integrally connected together at their upper ends by an upper bight or bend 11, which is adapted to rest on the bill 12 of the elevator hook 13. The upper ends of these elevator links are usually offset laterally, so that when in use, the upper ends of the links converge as indicated in Figure 1, and the adjacent sides of the links usually have rounded cheeks 14 to engage against each other.

The lower ends of the reins 10 are connected 90 by an integral bend or bight 15. (See Fig. 4.)

In applying my invention to a link of this type, I form the middle plane of the bight 15 so that it is oriented on the longitudinal axis of the link with respect to the plane of the bight 11 at the upper end of the link. This effect may be attained by twisting the lower end of the link as indicated in Figure 1, so that the lower ends of the two reins 10 are not located in a plane normal to the radial axis of the lug 6. In other words,

the plane of the lower bight 15 is oriented in a direction toward a plane substantially at right angles to the radial axis of the corresponding lug 6 when the elevator is open. In this connection, reference is had to Figure 3, in which the dotted lines 16 indicate the medial plane of the bights of the links 8 and 9. Preferably the amount of orientation is sufficient to enable the medial plane 16 to be substantially at right angles 10 to the longitudinal axis of the corresponding lug when the elevator is in its open position. When the elevator sections are swung toward each other to close the elevator, the lower ends of the links move inwardly with the corresponding lugs, and 15 assume the relation indicated in Figure 2, in which 6a indicates the lugs, 15a indicates the lower bights of the links, and 1a and 2a indicate the sections of the elevator.

If desired, the lower end 17 of a link of this 20 type may be bent laterally toward the vertical axis of the elevator. In other words, it may be offset in the same general direction as the upper end 18 of the link. This enables the bight 19 of such a link to fit in closer to the body of the 25 elevator section to which the link is attached, so that the links can get under the load which is being supported.

In Figure 7 I illustrate an embodiment of my 30 invention in a link 20 of a type called "weldless" link, because this type of link can readily be formed from solid metal by punching out an elongated eye 21 in the body of the link and providing a single shank 22 with which the reins 23 of the link integrally connect. The lower end 35 of the link is formed into a head 24 in which an eye 25 is punched so that the bottom of this eye constitutes a bight 26 corresponding to the bight 15 of the "hairpin" type link.

In this weldless type of link the medial plane 40 of the eye and of the bight 26 is oriented as indicated in Figures 2 and 3. This effect may be attained by forming a twist in the shank 22 while forging a link.

It will be evident that when links embodying 45 my invention are employed with an elevator composed of hinged sections, the links do not hinder in any way, the free movement of the elevator sections 1 and 2 in opening and closing the elevator, and in the open position of the elevator 50 the medial plane of the eye or bight that engages the lug on the adjacent section, is substantially at right angles to the radial line or radial axis of the lug. Therefore, the weight of the elevator on the links, does not tend to close the 55 elevator, and it will readily remain in an open position when being hoisted to an elevated point in the oil well derrick.

It is understood that the embodiment of the 60 invention described herein is only one of the many embodiments this invention may take, and I do not wish to be limited in the practice of the invention, nor in the claims, to the particular embodiment set forth.

I claim:

65 1. In a casing elevator construction for oil wells, the combination of an elevator having two sections with a hinge connection between the same enabling the elevator to swing open, each

of said sections having a radially projecting means for engaging an elevator link, and a pair of links for supporting the elevator, each of said links having a bight at its upper end for engaging an elevator hook, and having a lower bight rigid with the upper bight for engaging its corresponding projecting means, the plane of the lower bight of each link being oriented on the longitudinal axis of the link toward a plane inclined to the radial axis of the corresponding projecting means when the elevator is closed.

2. In a casing elevator construction for oil wells, the combination of an elevator having two sections with a hinge connection between the same enabling the elevator to swing open, each of said sections having a radially projecting means for engaging an elevator link, and a pair of links for supporting the elevator, each of said links having a bight at its upper end for engaging an elevator hook, and having a lower bight rigid with the upper bight for engaging its corresponding projecting means, the plane of the lower bight of each link being oriented on the longitudinal axis of the link into a plane substantially at right angles to the radial axis of the corresponding projecting means when the elevator is open.

3. An elevator link for supporting an elevator composed of two sections with a hinge connection between the same, said link having an upper bight at its upper end for engaging an elevator hook, and having a shank with an eye at its lower end for engaging the elevator, said eye being oriented on the longitudinal axis of the link with respect to the plane of the upper bight, so that in the closed position of the elevator the plane of the eye is inclined to the vertical radial plane passing through the central axis of the elevator and the eye.

4. A pair of elevator links for supporting an elevator composed of two sections with a hinged connection between the same, each of said links having a pair of oppositely disposed reins with a bight connecting the same at their upper end for engaging an elevator hook, said link having a lower bight connecting the lower ends of said reins, the plane of said lower bight being oriented on the longitudinal axis of the link with respect to the plane of the upper bight, so that in the closed position of the elevator, the plane of each lower bight is inclined to the vertical radial plane passing through the central axis of the elevator and the lower bight.

5. An elevator link for supporting an elevator composed of two sections with a hinged connection between the same, said link consisting of a single rigid piece having a pair of oppositely disposed reins with a bight connecting the same at their upper end for engaging an elevator hook, said link having a lower bight connecting the lower ends of said reins, the plane of said lower bight being oriented on the longitudinal axis of the link with respect to the plane of the upper bight, the upper end of said link being offset laterally and the lower end of said link at the lower bight being offset laterally in the same general direction as the offset at the upper end of the link.

CHESTER A. LUNDEEN.
